DESIGN FOR A SWITCH HOUSING

Victor L. Darnell, Centerville, Ohio, assignor to
The Master Electric Company, Dayton, Ohio, a
corporation of Ohio

Application May 3, 1944, Serial No. 113,446

Term of patent 14 years

(Cl. D26—13)

To all whom it may concern:

Be it known that I, Victor L. Darnell, a citizen of the United States, residing at Centerville, Montgomery County, Ohio, have invented a new, original, and ornamental Design for a Switch Housing, of which the following is a specification, reference being had to the accompanying drawing, forming a part thereof, in which

Fig. 1 is a front perspective view of a switch housing showing my new design.

Fig. 2 is a rear perspective view thereof, and
Fig. 3 is a top plan view thereof.

I claim:

The ornamental design for a switch housing,
substantially as shown.

VICTOR L. DARNELL.
